COKE CLEANING DEVICE

George J. Langmyhr, Sarnia, Ontario, Canada,
assignor to Standard Oil Development Company, a corporation of Delaware

Application March 19, 1936, Serial No. 69,673

2 Claims. (Cl. 15—104.10)

This invention relates to improvements in a device for cleaning the interior of hollow vessels such as the reaction chambers or soaking drums of oil treating apparatus and to some extent 5 has been described in my previous application Serial No. 652,685, filed January 20, 1933.

It is an object of this invention to provide 10 a guide which will prevent swaying of the driving or boring shaft or ram of the cleaner. It is a further object of this invention to provide for 15 lubrication of the guide. Another object is to provide for cooling of the boring shaft and the guide coupling to prevent crystallization of the boring shaft coupling caused by the alternate heating and cooling effect thereon during the 20 cleaning operation. Still another object is to provide a construction whereby the hydrocarbon gases contained in the vessel can be replaced with steam.

25 Other objects will be apparent from the specification and from the accompanying drawings, in which latter—

Fig. 1 is a vertical sectional view through a preferred form of apparatus for carrying out the 25 invention.

Fig. 2 is a detail vertical sectional view through a portion of a soaking drum, showing the head of the cleaning device in engagement with the coke and showing the guide in its operative 30 position, a portion of the guide and shaft being broken away.

Fig. 3 is a transverse sectional view taken along the line III—III of Fig. 2.

Fig. 4 is a detail view of the annular hinged hub for supporting the guide arms.

Fig. 5 is a vertical sectional view of the structure for effecting rotary movement of the drive shaft.

Fig. 6 is a transverse sectional view taken 40 along the line VI—VI of Fig. 5; and

Fig. 7 is a detail vertical sectional view of the ram structure for effecting longitudinal movement of the drive shaft.

Referring to the drawings, reference numeral 45 1 designates the metallic shell of a receptacle such as a soaking drum used in the heat and pressure treatment of hydrocarbon oil. The shell 1 is lined with a layer of reinforced concrete 2. During the heat and pressure treatment 50 of hydrocarbon oils in the soaking drum, the contents of the drum are subjected to conditions which result in the deposit of a layer of coke 4, or the like, upon the wall of the drum. This layer 4 of coke becomes sufficiently thick to 55 necessitate shutting down of the heat and pres-

sure treatment of the oil, so that the drum can be cleaned of the deposit of coke. The shell of the drum 1 normally converges to a relatively small manhole at its bottom, as illustrated in Fig. 1. The man-head is removed and the head of the excavating device is introduced through the manhole. Ordinarily, this is done before the contents of the soaking drum have had an opportunity to cool down to atmospheric temperatures.

The cleaning or excavating device comprises a tubular arm or shaft 6 provided with a reamer head 12 having annularly projecting cleaner arms 7, which are adapted to engage and grind away the layer of coke 4. The excavating device is 15 driven in rotation by driving device 8 disposed exteriorly of the soaking drum.

The upper end of the shaft 6 is provided with a guide to retain the shaft and cleaner arms 7 in predetermined spaced relationship from the wall 20 of the reaction chamber. The shaft 6 is provided with a bushing 13 which is rigidly secured to the shaft 6 in any suitable manner. The guide comprises a frame formed of a split hub 15 hinged at 16, the sections of the split hub being locked 25 together at 17. The split hub 15 is provided with a plurality of spaced arms 20. The arms 20 carry outwardly extending arms 22 which are pivoted between the arms 20 for vertical pivotal movement by means of pins 24. The arms 22 carry 30 rollers 25 at their outer ends. The rollers 25 protrude radially outwardly to a greater distance than the arms 7 of the reamer head. The arms 22 can be pivoted upwardly to permit of the introduction of the guide through the relatively 35 small manhole of the soaking drum. The arms 22 are provided with shoulders 26 which bear against the hub 15 when the arms 22 are in their radial position, to prevent the arms 22 from dropping downwardly to a position in which they 40 would be inoperative to function as guides.

The excavating device is moved longitudinally into the reaction vessel by an hydraulic lift. The hydraulic lifting apparatus includes a base 30 from which a casing 31 depends. An hydraulic 45 cylinder 32 projects from the base 30 into the casing 31 in spaced relation to the casing 31, to form an annular space 33. The hydraulic cylinder is supported at its top by means of a head 36 associated with the base 30, and is supported 50 at its bottom by means of a shoe 37. The shoe 37 cooperates with the casing 31 and cylinder 32 to form the seal for the bottom end of the annular chamber 33. A bull plug 39 is attached to the bottom end of the casing 31. Water pressure for

the purpose of raising the drive shaft 6 longitudinally through the required height in the soaking drum, is introduced into the annular chamber 33, through a pipe line 41 from any suitable source of supply (not shown). The water is delivered from the annular chamber 33 into the lower portion of the hydraulic cylinder 32 through a plurality of ports 43.

The hydraulic pressure is transmitted to the drive shaft 6 through the following arrangement of parts. The drive shaft 6 carries at its lower end an assembly which comprises a cylindrical plunger 45 which completely fills the cross section of the hydraulic cylinder 32. The plunger stem 46 extends through the plunger 45 and at its upper end is secured to a lignum-vitae disc 47. The lignum-vitae disc 47 bears against a housing 48 containing lower and upper ball races 71 and 78 respectively. The upper ball race 78 is secured to the bottom end of the drive shaft 6 and held in place by a collar 79. The plunger 45 is adapted to be forced longitudinally upwardly in the casing 32 by the hydraulic pressure of the liquid contained in the portion of the casing 32 below the plunger, and designated 33a.

The excavating device is driven in rotation from a shaft 50 connected to a steam engine or the like (not shown). The shaft 50 rotates a pinion 51. The pinion 51 drives a rotary turntable 52 which is carried by a portable frame 54 so as to provide means for moving the cleaning device from one container to be cleaned to another. A drive bushing 55 is fitted to and securely attached to the rotary turntable 52. Keyways 56 are provided in the drive bushing 55 and keys 58 have a driving fit with the keyways and with suitable recesses in the drive shaft 6.

In utilizing the device for cleaning a soaking drum the device is positioned beneath the man-hole of the drum. Fluid, such as water or other non-inflammable liquid, is injected through the line 41 to cause the shaft 6 to be driven upwardly longitudinally through the manhole. Upon insertion of the upper end of the shaft 6 through the manhole, the cleaner arms 7 are secured to the head of the excavating device. The arms 22 are held in their pivoted position substantially parallel with the longitudinal axis of the shaft 6 until the guide arms have passed into the soaking drum, after which the guide arms 22 are permitted to pivot outwardly to the radial position, as illustrated in Figs. 1, 2 and 3. Rotary movement of the shaft 6 is now effected. The rotating reamer head 7 effects a grinding and wearing away of the deposit of coke from the interior of the vessel. The resulting strain upon the reamer head and shaft effects lateral sway thereof. This swaying action is prevented by engagement of the guides 22 with the cleaned wall of the drum. As a consequence, the reamer arms 7 are prevented from removing or injuring the lining 2 of the soaking drum. While a shell lined with reinforced concrete has been shown and described, it will be understood that the shell can be unlined, in which the guide rollers 25 prevent the reamer arm 7 from delivering damaging blows to the butt straps and rivets and wearing annular grooves in the forged steel reaction chamber. The guide rollers are therefore prevented from increasing the rate of corrosion and from promoting cracks in the shell.

Lubrication is effected between the bushing 13 and the hinged split hub 15 of the guide, through the following arrangement of parts. The connection between the tubular shaft 6 and the

reamer head 12 is effected by means of a tubular collar 60 which has screw threaded connection with the shaft 6 and with the reamer head 12. The end of the tubular shaft 6 is formed into a reservoir 61 for lubricant by means of partition plates 63 and 64, which are secured in fluid-tight relation to the inner walls of the shaft 6. The lubricant is introduced into the lubricating chamber 61 by removing a plug 67. The lubricant is delivered from the lubrication chamber 61 to lubricate between the hinged split hub 15 and the bushing 13 by means of a port 65 which opens through the wall of the tubular shaft 6 and through the bushing 13.

Crystallization of the boring shaft and couplings caused by the alternate heating and cooling effect on boring shaft and couplings during the cleaning operation, is prevented through the following construction. A portion of the water used for raising the drive shaft 6 through the required height in the soaker is by-passed into the tubular shaft, as follows. The water passes from the chamber 33a through apertures 70 in the protruding end of the plunger stem 46 into the bore 71, which extends longitudinally of the stem. The bore 71 communicates with bores 73 and 74 in the lower and upper ball races 71 and 78 respectively. The bore 74 opens into a passageway 75 through the collar 75 which passageway in turn communicates with one in the end of the hollow shaft 6. The water is forced upwardly through the entire length of the drive shaft and flows upwardly through tubes 80 extending through the lubricant reservoir, 61, where it functions to cool the coupling of the hub 15 to the shaft 6 through the medium of the lubricant in the reservoir 61. The hydraulic fluid flows from the tubes 80 into a chamber 81 formed in the end of the shaft 6, and is delivered from the chamber 81 through a port 82 laterally against the shell of the container 1. The hydraulic fluid is relatively cool in temperature and functions to prevent over-heating of the shaft 6 and the hub of the guide. The hydraulic liquid therefore insures free turning movement of the hub 15. The stream of water ejected through the port 82 from the rotating tubular shaft 6 assumes a spray-like form which facilitates the transformation of the water into steam upon striking the hot walls of the container 1. The steam displaces the highly explosive mixture of oil vapor and air, which normally forms within the reaction chamber 1. The jet of water tends to keep down the dust which forms as a result of the grinding away of the layer of coke by the reamer arms 7.

Various changes may be made within the scope of the appended claims in which it is desired to claim all novelty inherent in the invention as broadly as the prior art permits.

I claim:

1. An excavating device having a head for removing solids from a container and a tubular shaft for rotating and advancing the head through the container, a guide for the head including a collar rotatively mounted on the shaft, a lubricant reservoir in the portion of the shaft adjacent the collar, a port opening through the shaft from the reservoir into the bearing between the collar and shaft, hydraulic means including non-inflammable liquid for advancing the shaft, means for diverting a portion of the non-inflammable liquid into the shaft, and tubes extending from the interior of the shaft through the reservoir for cooling the lubricant.

2. An excavating device having a head for removing solids from a container and a tubular shaft for rotating and advancing the head through the container, a guide for the head including a collar rotatively mounted on the shaft, a lubricant reservoir disposed within the shaft adjacent the collar, a port opening through the shaft from the reservoir into the bearing between the collar and shaft, a fluid chamber disposed within the shaft above said reservoir, a plu-

rality of tubes extending through said reservoir connecting said fluid chamber with the interior of the shaft, hydraulic means for advancing the shaft, including a non-inflammable liquid, means for diverting a portion of said liquid into the interior of the shaft below said reservoir, and a port discharging through the wall of said shaft from said chamber to permit a constant flow of liquid through the tubes in said reservoir.

GEORGE J. LANGMYHR.
